UNITED STATES PATENT OFFICE.

JULIUS N. CAYO, OF GARY, INDIANA.

CAN-OPENER.

1,276,620.

Specification of Letters Patent. Patented Aug. 20, 1918.

Application filed December 22, 1916, Serial No. 138,430. Renewed July 6, 1918. Serial No. 243,707.

To all whom it may concern:

Be it known that I, JULIUS N. CAYO, a citizen of the United States, residing at Gary, in the county of Lake and State of Indiana, have invented new and useful Improvements in Can-Openers, of which the following is a specification.

The present invention has reference to can openers so constructed as to efficiently cut 10 a circular opening in the top of the can, and is directed more specifically to the adjustable cutting means, and is designed primarily as an improvement upon Patent No. 1,189,058, and granted to me under date of June 27, 15 1916.

Furthermore, I contemplate the production of a can opener of the above stated character which may be manufactured at comparatively low cost, is efficient in use, and 20 may be readily operated, and one whereby the same may be applied to cans of different sizes for cutting an opening in the can of the desired diameter.

With the above and other objects in view, 25 the invention consists in the novel features, details of construction and combination of parts which will hereinafter be more fully set forth, illustrated in the accompanying drawing and pointed out in the appended claim.

30 Figure 1 is a vertical sectional view of a can opener constructed in accordance with my invention;

Fig. 2 is a perspective view of the adjustable cutter; and

35 Figs. 3 and 4 are detail views of the opener.

Referring more particularly to the accompanying drawing, in which like characters of reference refer to corresponding parts in 40 the several views, use is made of a can opener comprising a circular housing 5 preferably constructed of sheet metal or the like material and provided at its lower end with an annular flange 6. The flange 6 of the housing is secured to a base plate 7, as denoted by the character 8 and this base plate 7 not only performs the purpose of closing the housing against the entrance of dust or dirt therein, but the corner portions 9 of the base 45 plate protrude beyond the marginal edge of the base flange 6, thus serving as grips affording convenient means for holding the opener during the opening action of a can or the like. An operating crank 10 is employed having its horizontal shaft portion 55 extending across the lower portion of the

housing and mounted in bearings 12 in the wall of the housing. The shaft 11 is provided adjacent one end thereof with a spur gear 13, one side of said gear projecting 60 through an elongated slot 14 provided in the base plate 11. Secured to the central portion of the base plate 7 and depending therefrom is a pin 15 on the free terminal of which is fixedly secured a circular plate 16 65 provided with a pair of diametrically arranged spurs 17, adapted upon the application of the opener to a can, to penetrate said can, thus preventing any accidental movement of the opener during the cutting of the 70 can. This circular plate 16 is spaced from the outer face of the base plate 7 to define between the confronting faces of the circular plate and the plate a space 18. Mounted upon the pin 15 for rotary movement and 75 rotating in the space 18, is a circular cutting plate 19, of a diameter greater than the diameter of the circular plate 16 to expose the gear openings 20 for the reception of the spurs of the gear 13. 80

I employ in connection with a can opener of the above stated character, means for adapting the opener to cut circular openings in cans of different diameters as so desired, and to this end, use is made of an adjustable 85 cutter 21. This cutter 21 is preferably constructed of high tempered steel or the like material and is stamped from a single piece of material to provide the same with a laterally extending elongated arm 22 provided 90 at the outer extremity thereof with an angular cutting blade 23. Formed on the opposite end of the arm 22 is a broadened flat fork-shaped head 24, and owing to the specific configuration of this head, that is to 95 say, the limbs 25 thereof being arranged in spaced parallelism one to the other, defines between the limbs and in axial alignment with the arm 22 a U-shaped slot 26 adapting the limbs 25 to straddle the pin 15. Owing 100 to the fact that the material of the adjustable cutter forming the head is of a width greater than the width of the arm 22, provides at the point of intersection of the head with the arm a pair of horizontal shoulders 105 27. The head 24 is slidably mounted between the confronting faces of the circular plate 16 and the circular cutting plate 19 for a horizontal sliding movement, and the rotation of the adjustable cutter independent of 110 the circular cutting plate, is accomplished due to the arm 22 operating in a U-shaped

guide 28 secured to the bottom face of the circular cutting plate 19 in juxtaposition to its marginal edge, while the provision of the shoulders 27 limits the outward horizontal movement of the adjustable cutter, and further the curved connecting portion 29 of the slot 26 serves to limit the inward stroke or movement of the adjustable cutter.

In briefly describing the operation of the device, it is to be stated that when it is desired to open the can, the spurs 17 of the circular plate 16 are forced into the can, the adjustable cutter moved in a lateral or horizontal position to the point of cutting a circular opening in the top of the can of the desired diameter, and then upon the turning of the crank 10 will impart a rotary movement to the circular cutting plate 19 which in turn moves the adjustable cutter in a circular path to perform the complete cutting within the can of a circular opening.

From the foregoing description, taken in connection with the accompanying drawing, the advantages of construction and the method of operation will be readily apparent to those skilled in the art to which the

invention relates, and while I have described the principles of operation of the invention, together with the device which I now consider to be the best embodiment thereof, I desire to have it understood that the device shown is merely illustrative, and that such changes may be made when desired as are within the scope of the appended claim.

What is claimed as new, is:—

A can opener comprising a base plate, a casing carried thereby, a shaft journaled in said casing, a spur gear on said shaft extending through a slot in the base plate, a pin carried by said base plate and projecting below the same, a holding plate carried by the end of said pin and spaced from the base plate, a circular plate having openings therein annularly arranged and adapted to be engaged by the said spur gear, a knife member having a forked end located between the bottom plate and said circular plate, the fork engaging the pin and a loop on said circular plate engaging with said knife member above the forked end.

In testimony whereof I affix my signature.

JULIUS N. CAYO.
